UNITED STATES PATENT OFFICE.

SAMUEL G. WELLS, OF CHICAGO, ILLINOIS.

LOCK FOR SWITCH-OPERATING DEVICES.

1,284,002.

Specification of Letters Patent.

Patented Nov. 5, 1918.

Application filed September 26, 1916. Serial No. 122,220.

To all whom it may concern:

Be it known that I, SAMUEL G. WELLS, a citizen of the United States, and a resident of the city of Chicago, county of Cook, and 5 State of Illinois, have invented certain new and useful Improvements in Locks for Switch-Operating Devices, of which the following is a specification.

My invention relates to improvements in 10 locking devices designed for use especially in connection with switch operating mechanism, and has for its object the production of a device of this character, through the medium of which, a switch operating device 15 may be readily and quickly locked in adjusted position, and which may be readily and easily unlocked by a switchman in throwing the switch. A further object is the production of a locking device, as mentioned, 20 which will be of durable and economical construction, one which will be proof against the weather, and which will be highly efficient in use. Other objects will appear hereinafter.

25 The invention consists in the combinations and arrangements of parts hereinafter described and claimed.

The invention will be best understood by reference to the accompanying drawings 30 forming a part of this specification, and in which,

Figure 1 is a perspective view of a conventional form of railway switch operating mechanism equipped with a lock, embodying 35 the invention,

Fig. 2, a front elevation of the lock, showing the lever, which is locked thereby, in section,

Fig. 3, a view similar to Fig. 2, with the 40 front plate of the housing of the lock removed,

Fig. 4, a section taken on line $x-x$ of Fig. 2,

Fig. 5, a view similar to Fig. 3, showing 45 another form of the lock,

Fig. 6, a view similar to Fig. 5, except that the lock is shown in unlocked position, and

Fig. 7, a section taken on line $Y-Y$ of 50 Fig. 5.

The preferred form of construction, as illustrated in the drawings, is designed for use preferably in connection with the oscillatory operating lever 1 of a conventional switch operating device, as shown in Fig. 1. 55 The lock comprises a housing 2 of substan-

tially circular form in which is provided an upwardly opening socket 2' which is adapted to receive the lever 1 as shown in the several views. Housing 2 is provided with a suitable base 3 whereby the same may be rigidly secured to a railway tie or other suitable support. The front side of housing 2 is closed by a plate 4 which is secured in position by means of screws 5.

Provided centrally in the housing 2 is a stud or shaft 6 upon which is rotatably mounted a latch 7. The latch 7 is formed with two stop lugs 8 and 9, as shown in the form of the lock illustrated in Figs. 2, 70 3 and 4. Coöperating with the latch 7 is a helical tension spring 10 adapted to normally hold said latch in unlocked or inoperative position. In this position of said latch, the lug 8 is in retracted position in the housing 2, the lug 9, however, being positioned to traverse the socket 2' so that upon downward rocking of the lever 1 into engagement with said socket, the same will engage with the lug 9 and cause the latch 7 to be rotated 75

into the position shown in Figs. 2 and 3. In the rocking of said latch into this position, the lug 8 will be moved into engagement with the upper side of the lever and thus serve as a means of holding or locking the 80 same in position in socket 2'. Said latch is locked in the last mentioned or operative position by means of a pawl or locking member 11 which is pivoted at 12 to one side of said latch. Said pawl coöperates with a stop lug 13 projecting from the bottom of housing 2, a helical torsional spring 14 coöperating with said pawl whereby, in the rocking of latch 7 to operative or locking position, as just described, said pawl will be 85 brought into operative relation with the lug 13, as clearly shown in Fig. 3, and thus effect automatic locking of the latch in operative or locking position. Unlocking of lever 1 may be effected only through the medium 90 of a key which may be inserted through a key hole 15 formed in the plate 4, a key thus inserted, being adapted, upon rotation, to engage with the lower edge of pawl 11 and raise the same from operative relation with stop lug 13. A stop lug 16 is also 95 formed in housing 2 for limiting downward rocking of the latch to operative position as shown in Figs. 2 and 3.

In the form shown in Figs. 5, 6 and 7, a 110 latch 7' is formed with stop lugs 8' and 9' for coöperation with lever 1, said latch being

locked in operative or locking position by means of a pawl 17 which is pivotally mounted in housing 2 as at 18. Said pawl 17 is adapted for engagement with a stop 5 shoulder 19 provided at the upper end of the latch, said latch being cut away as at 20 to afford clearance for the pawl upon upward rocking of the latter, to permit of movement of the latch to unlocked position 10 under the influence of spring 10. In this form one end of spring 10 is connected with pawl 17 so that said spring serves the double function of means for normally holding said pawl in operative position and for rotating the latch to releasing position, when 15 said latch is unlocked. The pawl 17 is rocked to releasing position through the medium of a cam 21 which is pivotally mounted upon the stud 6 of housing 2. A torsional spring 22 coöperates with the cam 21 to normally hold the same at its lower or 20 inoperative position against a stop 23. The arrangement is such that upon upward rocking of said cam, the same is adapted to engage against the adjacent curved end of pawl 17 thereby effecting upward rocking of the same to releasing position. This 25 movement of said cam is effected by means of a key, shown in dotted lines at 24 in Fig. 6, which may be inserted through a key hole 25 formed in the plate 4.

With the construction set forth it will be seen that in locking the lever 1 in position, it is only necessary to rock same downwardly into engagement with the socket 2'. When this is done, said lever will engage with and rotate the latch to locked position, thus serving to automatically lock said lever in this position. When it is desired to unlock said lever it is only necessary to insert a key of proper form into the key hole and rotate the same as above described. The construction is simple and economical, the same being not susceptible to readily become 40 inoperative. In order to effectually exclude the weather, the cover 4 is formed with an internal shoulder as clearly shown in Figs. 4 and 7 which forms a broken joint between said cover and the housing. An annular 45 flange 26 at the inner side of cover 4 is provided for engagement with the flanged front side of the latch in order to guide the latter in the rocking or oscillatory movement of the same.

While I have illustrated and described the 55 preferred form of construction for carrying my invention into effect, this is capable of variation and modification without departing from the spirit of the invention. I, therefore, do not wish to be limited to the 60 precise details of construction set forth, but desire to avail myself of such variations and modifications as come within the scope of the appended claims.

Having described my invention what I 65 claim as new and desire to secure by Letters Patent is:

1. In a lock of the class described, the combination with a lever to be locked, of a housing having a socket therein adapted to receive said lever; a latch rotatably mounted in said housing adapted to hold said lever in position in said socket; stops on said latch adapted for engagement with said lever; means for locking said latch against rotary movement; and resilient means for automatically moving said locking means into operative relation with said latch upon rotation of the latter into operative position and for normally holding said locking means 80 in operative position and for rotating said latch to releasing position when said latch is unlocked, substantially as described.

2. In a lock of the class described, the combination with a lever to be locked, of a housing having a socket therein adapted to receive said lever; a latch rotatably mounted in said housing to hold said lever in position in said socket; stops on said latch adapted for engagement with said lever; a pivotally mounted pawl for locking said latch against rotary movement; and resilient means connecting said pawl and said latch for automatically rocking said pawl into operative relation with said latch upon rotation of the latter into operative position and for normally holding said pawl in operative position and for rotating said latch to releasing position when said latch is unlocked, substantially as described.

In testimony whereof I have signed my name to this specification in the presence of two subscribing witnesses.

SAMUEL G. WELLS.
